DESIGN FOR A TRIPOD MOUNTED
FLASHLIGHT

Michael Garlinski, Thorold, Ontario, Canada

Application May 28, 1947, Serial No. 139,347
In Canada December 9, 1946

Term of patent 14 years

(Cl. D48—24)

To all whom it may concern:

Be it known that I, Michael Garlinski, a citizen of Poland and resident of the town of Thorold, county of Welland, Province of Ontario, in the Dominion of Canada have invented a new, original, and ornamental Design for Tripod Mounted Flashlight, of which the following is a specification, reference being had to the accompanying drawings, forming part thereof.

The drawings represents in Figure 1 a plan view of a tripod mounted flashlight showing my new design, and Figure 2 is an elevational view.

I claim:

The ornamental design for a tripod mounted flashlight, as shown.

MICHAEL GARLINSKI.
